UNITED STATES PATENT OFFICE.

LEWIS L. TATUM, OF MILWAUKEE, WISCONSIN, ASSIGNOR TO THE CUTLER-HAMMER MFG. CO., OF MILWAUKEE, WISCONSIN, A CORPORATION OF WISCONSIN.

RHEOSTAT.

1,112,170.

Specification of Letters Patent. Patented Sept. 29, 1914.

Application filed February 10, 1913. Serial No. 747,420.

To all whom it may concern:

Be it known that I, LEWIS L. TATUM, a citizen of the United States, residing at Milwaukee, in the county of Milwaukee and 5 State of Wisconsin, have invented new and useful Improvements in Rheostats, of which the following is a full, clear, concise, and exact description, reference being had to the accompanying drawing, forming a part 10 of this specification.

My invention relates to improvements in rheostats and more particularly to rheostats in which the resistance thereof is mounted in or upon a heat absorbing body. Such 15 rheostats are used for various different purposes and are very commonly used in theater dimmers.

In the rheostat plates of theater dimmers, and also of various other forms of controllers, it has been customary to portion off the 20 surface of the supporting base or plate into equal spaces for the various steps of resistance. Further, it has been customary to proportion the various steps of resistance 25 so that the maximum rate of heat dissipation will be substantially equal, considering the same individually. This provides an equal maximum rate of heat dissipation on practically all portions of the plate, but as 30 successive steps of resistance are cut into circuit the current in the preceding steps is reduced with a corresponding reduction in the heat dissipated thereby. Thus in operation a large portion of the base or plate 35 available for heat absorption is practically inactive or at least only utilized to a small degree of its maximum capacity.

My invention has for one of its objects to provide a rheostat structure wherein a heat 40 absorbing base of a given size may be utilized to absorb the heat of a materially greater amount of resistance without at any time overtaxing the capacity of any portion thereof.

45 A further object is to produce a duplex rheostat in which each section thereof will utilize for heat dissipation the available capacity of the base not utilized by the other section and in which the total heat dissipation 50 of the two sections at any point on the base will not exceed or at least will not materially exceed the maximum heat dissipa-

tion at such point by a single section. The advantages of such a rheostat are at once obvious. For example, it provides for economy of material and economy of space, both 55 of which are very important features in rheostats.

Various other objects and advantages of my invention will hereinafter appear. 60

In order to more fully and clearly disclose the nature and advantages of my invention I shall describe the rheostat illustrated in the accompanying drawing, which embodies my invention in one form. It should, of 65 course, be understood that my invention might be embodied in other forms having all the advantages of the form selected for illustration.

In the drawing, Figure 1 is an elevation 70 of the rheostat; and, Figs. 2 and 3 are views of opposite sides thereof.

The rheostat selected for the purpose of illustration is one particularly adapted to use in theater dimmers but, of course, it 75 might be used in other relations. Briefly described, it comprises two substantially identical sets of resistances 1, 1^a, and 2, 2^a, mounted upon opposite sides of a common supporting plate or base 3 of suitable heat 80 absorbing capacity. The sets of resistances 1, 1^a, and 2, 2^a, are provided with separate controlling elements 4 and 5 respectively, and, as will be hereinafter more fully set forth, the resistances are arranged in such 85 relation on the base as to cause each to utilize for heat dissipation that portion of the base which is not utilized, or at least not utilized to its full capacity, by the other resistance, and to insure against the heating 90 of any portion of the base to any materially greater extent than it would be heated by a single resistance under maximum heat conditions at that portion.

In practice any preferred form of base 95 and resistance may be employed and the resistance may be mounted upon the base in any preferred manner. As illustrated, the base is of circular form with the sets of resistances embedded in the opposite faces 100 thereof. The base 3 is preferably formed of soapstone or other non-conducting heat absorbing material. The resistances preferably comprise reflexed resistance wires set

into annular recesses 6 in opposite faces of the base 3. The resistances are divided into steps by contacts 7 of any suitable type and preferably arranged in arcs concentric with the center of the plate 3. The resistance and contacts are secured to the plate 3 by a cement filler within the annular recesses 6. The resistances 1, 1^a, 2, and 2^a are adapted to be connected to terminals 8, 9, 10 and 11 respectively, mounted on the periphery of the plate 3. The controlling elements 4 and 5 each comprise a single conducting bar fulcrumed upon a spindle 12 concentric with the arcs of the contacts and each is provided at opposite ends with brushes adapted to engage diametrically opposite contacts on one side of the base.

Referring to Figs. 2 and 3 it will be observed that the circuit connections are such that each arm when moved in one direction will increase both sections of its respective set of resistances and when moved in the opposite direction will decrease both sections thereof. Further referring to Figs. 2 and 3 it will be observed that the line of division between the resistance sections 1 and 1^a is perpendicular to the line of division between the resistance sections 2 and 2^a. Accordingly, the controlling elements 4 and 5 when in corresponding positions with respect to their individual resistances will be 90° apart. Hence, if both controlling elements be moved simultaneously the resistance sections inserted in circuit thereby will be 90° apart and they will dissipate heat to portions of the base 90° apart. Such being the case, each will dissipate heat to that section of the base which is inactive with respect to the other set of resistances and this same condition will prevail for 90° rotation. Continued rotation will then cause gradual insertion of resistance directly opposite the previously inserted resistance on the other side of the base. Under such conditions the opposite sections of resistance will transmit heat to the same portions of the base. As before stated, however, the rate of heat dissipation by the individual steps of resistance is decreased by the insertion in circuit of subsequent steps of resistance. Accordingly, with the resistance arranged as described, it will be obvious that when two opposite steps of resistance are inserted in circuit one section will be dissipating heat at a materially reduced rate so that the total amount of heat dissipated by the two sections will not be excessive.

The advantages of the above described arrangement increase as the adjustable resistance of the controlled circuit is increased relatively to the fixed resistance thereof. This is because an increase between the adjustable and fixed resistance increases the

range of heat dissipation to the different portions of the base, and thus increases the area of the base which is inoperative or worked below maximum capacity.

As an example of the range of heat variation, let it be assumed that it is desired to regulate a bank of lamps having a resistance of 5 ohms on a 100 volt circuit by a rheostat or dimmer resistance of 15 ohms, the resistance being arranged in steps of such value that the maximum value of watts dissipated in each step shall be the same. If R is the ohmic value of the first step of resistance to be cut into circuit, then the maximum watts dissipated on that step will be the square of the maximum current times the resistance, or approximately $20^2 R$ or 400 R. When all the resistance is in circuit the current is reduced to 5 amperes but since the value R on the step remains unchanged the watts of the step are only $5^2 R$ or 25 R. Thus the minimum watts on the step are only 6.3% of the maximum watts. This reduction is gradual as the resistance is cut into circuit and the current reduced. Thus where resistance is placed upon each side of the base the more the current is reduced by the resistance on one side the greater may be the energy dissipated by the correspondingly located resistance on the other side of the base without the sum of the two exceeding a safe value.

What I claim as new and desire to secure by Letters Patent is:

1. A rheostat comprising a heat absorbing base, and adjustable resistances mounted on opposite sides thereof with their successive steps in relatively different positions with respect to said base.

2. A rheostat comprising a heat absorbing base, adjustable resistances mounted on opposite sides thereof to transmit heat thereto, the steps of resistances at corresponding points on opposite sides of the base being separated from their respective terminals by resistances of different values.

3. A rheostat comprising two resistances, and a common supporting base therefor arranged between the same, said resistances being arranged in different relations with respect to said base whereby when both resistances transmit heat to the same portion or portions of the base the rate of heat dissipation of one resistance will be reduced.

4. A rheostat comprising two adjustable resistances, a common supporting base therefor arranged between the same to absorb heat therefrom, said resistances being of different values between their respective terminals and corresponding points on opposite sides of said base throughout their respective lengths.

5. A rheostat comprising a heat absorbing base, resistances mounted on opposite

sides thereof, and controlling elements mounted on opposite sides of said base for adjusting said resistances, said elements throughout their entire range of movement having different relative positions for corresponding control of their respective resistances.

In witness whereof, I have hereunto subscribed my name in the presence of two witnesses.

LEWIS L. TATUM.
